[57] CLAIM

The ornamental design for a urinary catheter, as shown and described.

DESCRIPTION

FIG. 1 is a perspective view of a urinary catheter, showing our new design;

FIG. 2 is an end elevational view thereof;

FIG. 3 is a side elevational view thereof;

FIG. 4 is an end elevational view thereof, opposite that shown in FIG. 2;

FIG. 5 is a top plan view thereof;

FIG. 6 is a bottom plan view thereof;

FIG. 7 is a side elevational view thereof, opposite that shown in FIG. 3;

FIG. 8 is a perspective view of a second embodiment of FIG. 1;

FIG. 9 is an end elevational view thereof;

FIG. 10 is side elevational view thereof;

FIG. 11 is an end elevational view thereof, opposite that shown in FIG. 9;

FIG. 12 is a top plan view thereof;

FIG. 13 is a bottom plan view thereof; and

FIG. 14 is a side elevational view thereof, opposite that shown in FIG. 10.
